UNITED STATES PATENT OFFICE.

NELSON BREAKENRIDGE, OF REDLANDS, CALIFORNIA.

DELIVERY-CASE FOR BOTTLED GOODS.

No. 850,561.

Specification of Letters Patent.

Patented April 16, 1907.

Application filed July 10, 1906. Serial No. 326,632.

To all whom it may concern:

Be it known that I, NELSON BREAKENRIDGE, a citizen of the United States, residing at Redlands, in the county of San Bernardino and State of California, have invented new and useful Improvements in Delivery-Cases for Bottled Goods, of which the following is a specification.

My invention relates to cases for delivering bottled goods, such as milk, where the seller delivers the full bottle and receives back from the purchaser the empty bottle; and the object thereof is to provide a case in which the vendor may lock the full bottle of goods in the case and take therefrom the empty bottle and the customer unlocks the door of the compartment containing the full bottle by putting the empty bottle into the case. I accomplish this object by the mechanism described herein and illustrated in the accompanying drawing, which is a perspective view of a delivery-case embodying my invention with parts broken away for clearness of illustration.

In the drawing, 1 is a case, preferably of wood, which has two compartments 2 and 3 therein. Compartment 3 is smaller than compartment 2, and the bottom 4 thereof is a short distance above the bottom 5 of compartment 2, which compartment extends under compartment 3. One side of the case forms a door 6, which is provided with a lock 7. This door when closed and locked forms the side closure for the adjacent openings of compartments 2 and 3. Compartment 3 is also provided with another opening, which is closed by a door 8, which has hinges 9 at the bottom thereof. Door 8 has a lug 10 at the top and on the inside thereof, which lug has an aperture 11 extending therethrough, into which is received the downturned end of the locking-bar 12 when door 8 is in its locked position, said bar being the means by which the door is locked. Bar 12 is carried by a platform 13, which is secured by hinges 14 to a support 15 on the bottom of the case. As shown in the drawings, one end of this platform, which for purposes of designation I will term the "outer" end, projects beneath compartment 3, which I will term the "full-bottle compartment," and the same is a little wider than compartment 3, so that the locking-bar is carried outside of the compartment and extends over and down through the top of the compartment, as shown. The outer end of

platform 13 carries a slide-bar 16, to the top of which is secured the locking-slide 17, which is vertically movable upon pins 18, which pins pass through slots 19 in the locking-slide and are secured in the wall of compartment 3. In 60 the top of the case is an opening which is large enough for the passage therethrough of the bottle 20. This opening is closed by a door 21, which is connected by hinges 22 to the top of the case so that it may swing downwardly 65 and inwardly. A coiled spring 23 normally holds this door in its closed position. At the rear end and on the lower side thereof and secured to this door is a lug or bar 24, behind which slide 17 moves whenever a bottle rests 70 upon platform 13, as shown in the drawing, thereby locking door 21.

I will describe my delivery-case as applied to delivering bottled milk. It will be understood that the delivery-case is securely fastened at the residence of the customer in a convenient position for access by the milkman, who carries the key to lock 7. When the milkman desires to deliver a bottle of milk to his customer, he unlocks door 7 and 80 puts the full bottle of milk in compartment 3, takes out the empty bottle from compartment 2, and locks the door. As soon as the empty bottle is removed from compartment 2 the outer end of platform 13 drops, thereby 85 carrying the end of locking-bar 12 into lug 10 and locking door 8 against being opened. At the same time locking-slide 17 drops down below lug 24, thereby unlocking door 21. The customer desiring the full bottle of milk 90 brings an empty bottle to the case and drops it into compartment 2 by pushing door 21 downwardly and inwardly. As soon as the bottle has passed the door spring 23 returns door 21 to its closed position. The bottle 95 passes on and rests upon the inner end of platform 13, and the weight thereof elevates the outer end of the platform, thereby carrying the locking-bar out of engagement with lug 10, so that the customer can open door 8 100 and take out the full bottle. At the same time the locking-slide 17 is moved upwardly back of lug 24, so that door 21 cannot be opened, and the empty bottle is locked in the case and cannot be removed therefrom, except by the milkman, who carries the key to lock 7. By this construction I provide a case which insures the delivery of the full bottle of milk to the customer and the empty milk-bottle to the milkman and prevents any 105

dispute between them, as the customer must deliver into the case an empty bottle before he can take therefrom the full bottle, and the milkman is always insured the delivery of the empty bottle, as it is locked in the case until he unlocks it to put a full bottle therein.

Having described my invention, what I claim as new is—

1. A case for delivering bottled goods containing two compartments having adjacent openings, and also having separated openings; a single closure for said adjacent openings; means to lock said single closure; closures for said separated openings; and mechanism for locking said separated closures, said mechanism being arranged to alternately lock one and unlock the other of said separated closures.

2. A case having two compartments therein, one of which is smaller than the other, said compartments having adjacent openings; a door secured to said case adapted to close said adjacent openings; a lock for said door; an independent door for the smaller of said compartments; an independent door for the larger of said compartments; and mechanism within the larger of said compartments to alternately lock and unlock the independent doors of said compartments, said mechanism being operable by a bottle placed within the larger of the compartments to unlock

the door of the smaller compartment and lock the door of the larger compartment.

3. The herein-described bottle-delivery case having two compartments therein provided with adjacent openings, one of said compartments being larger than the other and projecting below the smaller compartment; a door provided with a lock, said door being adapted to close the adjacent openings of said compartments; an independent door for the smaller of said compartments; hinges secured to the bottom of latter door; a lug having an aperture therein secured to the top of said last door; a door having a lug on the lower face thereof at the rear in the top of the case opening downwardly and inwardly into the larger of said compartments; a pivoted platform at the bottom of the larger compartment; and a locking-bar and a locking-slide carried by the outer end of said platform, said bar being adapted to lock the door of the smaller compartment and the slide to lock the door of the larger compartment.

In witness that I claim the foregoing I have hereunto subscribed my name this 3d day of July, 1906.

NELSON BREAKENRIDGE.
